(57) **CLAIM**

I claim the ornamental design for chess piece set, as shown and described herein.

DESCRIPTION

FIG. 1 is an angled perspective view of the dark pieces of the chess set.

FIG. 2 is a side perspective view of the dark pieces of the chess set.

FIG. 3 is a top view of a dark pawn piece of the chess set.
FIG. 4 is a perspective view of the dark pawn piece of the chess set.

FIG. 5 is a side view of the dark pawn piece of the chess set.
FIG. 6 is a side view of the dark pawn piece of the chess set.
FIG. 7 is a side view of the dark pawn piece of the chess set.
FIG. 8 is a top view of a dark knight piece of the chess set.
FIG. 9 is a perspective view of the dark knight piece of the chess set.

FIG. 10 is a side view of the dark knight piece of the chess set.

FIG. 11 is a side view of the dark knight piece of the chess set.

FIG. 12 is a side view of the dark knight piece of the chess set.

FIG. 13 is a top view of a dark rook piece of the chess set.
FIG. 14 is a perspective view of the dark rook piece of the chess set.

FIG. 15 is a side view of the dark rook piece of the chess set.

FIG. 16 is a side view of the dark rook piece of the chess set.

FIG. 17 is a side view of the dark rook piece of the chess set.

FIG. 18 is a top view of a dark bishop piece of the chess set.

FIG. 19 is a perspective view of the dark bishop piece of the chess set.

FIG. 20 is a side view of the dark bishop piece of the chess set.

FIG. 21 is a side view of the dark bishop piece of the chess set.

FIG. 22 is a side view of the dark bishop piece of the chess set.

FIG. 23 is a top view of a dark queen piece of the chess set.

FIG. 24 is a perspective view of the dark queen piece of the chess set.

(Continued)

FIG. 25 is a side view of the dark queen piece of the chess set.

FIG. 26 is a side view of the dark queen piece of the chess set.

FIG. 27 is a side view of the dark queen piece of the chess set.

FIG. 28 is an angled perspective view of the light pieces of the chess set.

FIG. 29 is a side perspective view of the light pieces of the inventive chess set.

FIG. 30 is a top view of a light pawn piece of the chess set.

FIG. 31 is a perspective view of the light pawn piece of the chess set.

FIG. 32 is a side view of the light pawn piece of the chess set.

FIG. 33 is a side view of the light pawn piece of the chess set.

FIG. 34 is a side view of the light pawn piece of the chess set.

FIG. 35 is a top view of a light knight piece of the chess set.

FIG. 36 is a perspective view of the light knight piece of the chess set.

FIG. 37 is a side view of the light knight piece of the chess set.

FIG. 38 is a side view of the light knight piece of the chess set.

FIG. 39 is a side view of the light knight piece of the chess set.

FIG. 40 is a top view of a light rook piece of the chess set.

FIG. 41 is a perspective view of the light rook piece of the chess set.

FIG. 42 is a side view of the light rook piece of the chess set.

FIG. 43 is a side view of the light rook piece of the chess set.

FIG. 44 is a side view of the light rook piece of the chess set.

FIG. 45 is a top view of a light bishop piece of the chess set.

FIG. 46 is a perspective view of the light bishop piece of the chess set.

FIG. 47 is a side view of the light bishop piece of the chess set.

FIG. 48 is a side view of the light bishop piece of the chess set.

FIG. 49 is a side view of the light bishop piece of the chess set.

FIG. 50 is a top view of a light queen piece of the chess set.

FIG. 51 is a perspective view of the light queen piece of the chess set.

FIG. 52 is a side view of the light queen piece of the chess set.

FIG. 53 is a side view of the light queen piece of the chess set; and,

FIG. 54 is a side view of the light queen piece of the chess set.
